UNITED STATES PATENT OFFICE.

WILLIAM O. BARNES, OF LEOMINSTER, MASSACHUSETTS, ASSIGNOR TO MARY E. JOHNSON, TRUSTEE, OF FITCHBURG, MASSACHUSETTS.

BREECH-LOADING FIREARM.

1,131,984.

Specification of Letters Patent. Patented Mar. 16, 1915.

Application filed August 24, 1914. Serial No. 858,209.

To all whom it may concern:

Be it known that I, WILLIAM O. BARNES, a citizen of the United States, residing at Leominster, county of Worcester, State of 5 Massachusetts, have invented an Improvement in Breech-Loading Firearms, of which the following description, in connection with the accompanying drawing, is a specification, like characters on the drawing representing like parts.

This invention relates to breech loading firearms and is particularly concerned with the firing mechanism and is particularly applicable to shot guns.

15 One object of the invention is to provide a hammer releasing mechanism of such a character that the hammer is readily released by a slight movement of, and a slight pressure upon, the trigger, and in which the sear 20 engages the hammer in a peculiar manner to secure efficiency of operation under these conditions.

Another object of the invention is to provide for the mounting of the sear mechanism and trigger mechanism both upon the trigger plate so that these mechanisms may be readily assembled and may, together with the trigger plate, be inserted and removed for repair or readjustment.

30 Another object of the invention resides in a construction of sear and trigger mechanism for a double barrel firearm which presents a simple, strong and efficient construction.

35 The nature and objects of the invention will appear more fully from the accompanying description and drawings and will be particularly pointed out in the claims.

The drawings represent the breech block 40 and connected parts of a double barrel shot gun embodying a preferred form of the invention.

In the drawings: Figure 1 is a side elevation partly in vertical cross-section of the 45 breech block of the gun, and connected parts; Fig. 2 is a plan view partly in horizontal section of the construction shown in Fig. 1; Fig. 3 is a perspective view of one of the hammers, and Fig. 4 is a bottom plan 50 view of a small portion of the construction shown in Fig. 1 to show the connection between the breech block and trigger plate.

While the invention is not restricted to a particular kind of firearm it is particularly 55 adaptable to breech loading shot guns and is

shown herein embodied in a construction for a double barrel breech loading shot gun.

The main parts of the mechanism with the exception of those particularly involving the invention are all well known and familiar 60 and need not be described in detail.

The breech block 1 is of the usual construction and is provided with the tang or top plate 2 extending rearwardly therefrom, while at the bottom the trigger plate 3 is interlocked therewith and secured thereto by the set screw 4 in a familiar manner. The trigger plate and the tang are connected together by screw studs 5 and 6 and the whole mechanism when assembled is inserted in 65 the gun stock and secured thereto in the usual way.

The hammer 7 is pivoted at 8 in the breech block and is thrown forwardly to firing position by the usual helical spring 9, into engagement with the firing pin 10. The hammer is provided at the top, with a lateral projection 11, forming a shoulder 12, and this shoulder is, by reason of its position, located at a very considerable distance from 70 the pivotal axis of the hammer. In the double barrel construction illustrated, the hammers are duplicates excepting that the projections 11 are both on the inside, facing 75 each other.

The trigger plate is provided with an upwardly projecting bearing block 13 and on this bearing block are pivotally mounted the sears and the triggers for operating the hammers. In the double barrel form of construction shown, this mounting is so arranged as to secure a very compact, strong, and simple form of construction. A bearing pin 14 extends through the forward end of the bearing block and on this bearing pin, 80 at each side of the bearing block is mounted a sear 15. Each sear has a forward arm 16 extending forwardly beneath the projection 11 and is provided with a hook 17 to engage the shoulder 12 on the hammer and hold it 85 back in firing position.

The bearing block 13 is provided at the rear with a pair of vertical slots 18. A bearing pin 19 extends through the rear of the bearing block and on this bearing pin are 90 pivoted, one in each slot 18, the triggers 20. Each sear at its rear end is bent inwardly at 21 to overlie the rear of the corresponding trigger. When now, the hammer 7 is thrown 95 backward by the cocking rod 22 against the 100 back in firing position.

The bearing block 13 is provided at the rear with a pair of vertical slots 18. A bearing pin 19 extends through the rear of the bearing block and on this bearing pin are 105 pivoted, one in each slot 18, the triggers 20. Each sear at its rear end is bent inwardly at 21 to overlie the rear of the corresponding trigger. When now, the hammer 7 is thrown 110 backward by the cocking rod 22 against the

action of the spring 9, its shoulder 12 snaps over and engages the hook 17 of the corresponding sear, the sear being thrown upwardly to effect this engagement by a small 5 spring 23 seated therein and engaging the trigger plate. With the parts thus in firing position it will be seen that a very slight pressure on the trigger will raise the rear end 21 of the sear, throwing the hook 17 10 out of engagement with the shoulder 12 and thus releasing the hammer. The engagement of the sear and hammer is effected at a very considerable distance from the pivotal axis of the hammer so that the leverage 15 is very considerable. Thus the hammer is readily retained in firing position by the sear but is readily released by a slight movement of the sear. The action of the trigger is therefore quick, and readily caused by a 20 slight pressure, making the firearm quick and accurate.

The construction disclosed for the mounting of the two sears and two triggers in the bearing block presents a very simple, compact, and strong construction in a double barrel firearm. The mounting of the sears and triggers on the trigger plate enables these parts to be readily assembled, in proper relative position and when assembled 25 on the trigger plate, readily to be inserted in position on the breech block and readily to be removed therefrom for repair or replacement.

Having fully described my invention, 30 what I claim as new, and desire to obtain by Letters Patent, is—

1. In a double barrel breech loading fire- 35 arm, the combination of a breech block, a

trigger plate removably connected to the breech block, and provided with an upwardly projecting bearing block, the said bearing block having a pair of vertical slots in the rear thereof, a bearing pin in the forward end of said bearing block, a pair of sears mounted on said bearing pin, one at 40 each side of said block, a second bearing pin in the rear of said block, a pair of triggers mounted on said bearing pin, one in each of said slots.

2. In a double barrel breech loading fire- 45 arm, the combination of a breech block, a trigger plate removably connected to the breech block, a pair of spring-pressed hammers pivoted on the breech block and each provided with projections near the top extending inwardly therefrom to form adjacent shoulders, a bearing block projecting upwardly from the trigger plate provided with a pair of vertical slots in its rear, a 50 pair of sears pivoted, one at each side on said bearing block and having their forward arms extending between the hammers and respectively beneath the corresponding shoulders on said hammers, each sear being provided with a hook to engage the corresponding shoulder, a pair of triggers, one pivoted in each of said slots and each trigger engaging with the rear arm of its corre- 55 sponding sear.

In testimony whereof, I have signed my name to this specification, in the presence of two subscribing witnesses.

WILLIAM O. BARNEs.
